INVENTOR.

Hardy Jackson,
By Donald O'Brien
Atty.

UNITED STATES PATENT OFFICE.

HARDY JACKSON, OF HIGHER BROUGHTON, MANCHESTER, ENGLAND.

ELECTRIC-ARC LAMP.

Application filed June 16, 1921. Serial No. 477,982.

To all whom it may concern:

Be it known that I, HARDY JACKSON, a British subject, residing at Higher Broughton, Manchester, England, have invented 5 certain new and useful Improvements in Electric-Arc Lamps, of which the following is a specification.

This invention relates to improvements in electric arc lamps and more particularly to 10 the arc lamp employed in projecting lanterns.

It consists in constructing the lamp with a standard hinged and pivotally mounted on a base and carrying two arms capable of 15 sliding up and down thereon. These are connected by pivoted levers with a nut mounted on a screw with a handle at one end, so that by the rotation of the screw the arms are brought nearer together as the carbons carry 20 thereon burn away, the handle also serving as a grip for tilting the standard to alter the vertical position of the arc gap between the carbons, and for twisting the standard on its base so as to move the 25 arc gap to one side or the other.

It consists further in the construction of the various parts of the apparatus as will be described.

The invention will be described with reference to the accompanying drawings.

Fig. 1 is a side elevation of apparatus.

Fig. 2 is a section on line $x-x$ Fig. 1.

Fig. 3 is a plan.

Fig. 4 is a section on line 4-4 Fig. 1.

The apparatus is constructed with a base plate A to which is attached by means of the cover plate A', a base piece A² which is hinged at b' to a standard B, preferably 35 circular in cross section. Two arms C C' which carry at their outer ends the carbons c c' are mounted on the standard B so as to be capable of sliding up and down thereon. A hole b is formed through the standard B to receive the end e (reduced in size) of 40 a rod E. A collar e' is affixed to the end of the rod E by a pin e² to prevent longitudinal movement of the rod E, but at the same time allowing it to freely rotate in the hole b in the standard B. The end of the 45 rod E is provided with a knob or handle E' by which it can be rotated and it is threaded for a portion of its length to receive a nut F attached to the arm C C' by the pivoted rods f. It will be seen that by 50 the rotation of the threaded rod E by the handle E' the arms C C' will be caused to

slide on the standard B and will be brought nearer together or farther apart according to the direction of the rotation of the rod E. Furthermore, by raising or depressing 60 the handle E' the inclination of the standard B can be altered, thus altering the height of the arc gap, or by pressing the handle E' sideways the base piece A² will cause to revolve on its centre together with 65 the standard B and the arms C C' thus moving the arc gap to one side or the other as may be required.

The top carbon holder G is made in two parts g g' affixed together by bolts or screws 70 and separated by a piece of insulating material g². The member g holds the carbon c and the member g' slides in the top arm C mounted on the standard B. The arm C is hollow throughout its length, in one end of 75 which the member g' slides, and a threaded rod H passes through it and engages a tapped hole g³ in the member g' to operate the latter. The arm C is provided with a loose portion g⁴ for the member g', the portion g⁴ 80 being held in position by screws c'. The threaded rod H is operated by a handle H' and a long slot in the standard B to allow the rod H to pass therethrough at whatever height on the rod H the arm C may be. 85 The rod H is held in position by grooved collar g⁵ in a recess in the arm C. It will thus be seen that by rotating the rod H the top carbon holder G can be moved in and out as desired for adjusting the position of 90 the top carbon c relative to the lower carbon c' to compensate for unequal burning of the carbons, and to adjust the crater.

The lower carbon holder K is made in two parts k k' affixed together by bolts or screws 95 and separated by a piece of insulating material k². The member k holds the carbon c and the member k' is pivotally mounted at c' on the lower arm C' sliding on the standard B. A projection M on the arm C' is 100 provided with a hole m in which a rod n is held in position by a pinned collar but free to rotate. The threaded part of the rod n engages a tapped hole in a nut n' pivotally mounted between the two plates forming the 105 link O pivoted to a projection k³ on the member k' of the carbon holder K. Thus, when the threaded rod n is rotated the holder K is moved on its pivot on lower arm C' to adjust the horizontal position of the carbon C. 110

The current is led to the carbon holders G and K from two terminals P P' arranged

behind the standard B, through flexible cables p p' to metal conductors p^2 p^3 affixed to the holders. The rods p^2 and p^3 extend to the rear of the apparatus so that the flexible leads p and p' will not be burnt by the heat of the arc.

This apparatus has considerable advantages over the usual electric arc lamps used in projecting lanterns, as it obviates the use 10 of expensive machine cut racks and pinions and worms and worm gears, which often become jammed by fragments of carbon; the different controls are more readily operated, and only three controls, one control giving 15 three movements, are necessary instead of the usual controls, five in number; it prevents the danger of the leads burning through and it is quicker in action.

What I claim as my invention and desire 20 to protect by Letters Patent is:—

1. An electric arc lamp applicable for use in projection lanterns comprising in its construction a central upright standard, a pivot on which it rocks, a base to which the 25 pivot is connected, two arms slidably mounted on the upright standard, a threaded rod carried by the upright standard, a nut on said rod, toggle levers connecting the arms to the nut by which their relative positions 30 are adjusted, a carbon holder slidably mounted on the upper arm, a pivot connected to the lower arm, a second carbon holder

carried by said pivot, a pivot connected to the lower carbon holder and a threaded rod to adjust the lower carbon holder angularly 35 in a plane at right angles to the standard.

2. An electric arc lamp applicable for use in projection lanterns comprising in its construction a central upright standard, a pivot 40 on which the standard rocks, a base to which the pivot is connected, two arms slidably mounted on the upright, a threaded rod carried by the upright standard, a nut on said rod, toggle levers connecting the arms to the 45 nut by which their relative positions are adjusted, a carbon holder slidably mounted on the upper arm, a pivot connected to the lower carbon holder, a threaded rod to adjust the lower carbon holder angularly in a plane 50 at right angles to the standard and metal conductors affixed to the carbon holders extending to the rear of the apparatus so that the flexible leads connected thereto will not 55 be burnt by the heat of the arc.

In testimony whereof I have hereunto set my hand in presence of two subscribing witnesses.

HARDY JACKSON.
